UNITED STATES PATENT OFFICE

2,471,900

METHOD OF PRODUCING FLATWARE

Fred S. Robinson, Yalesville, Conn., assignor to
R. Wallace & Sons Manufacturing Company,
Wallingford, Conn., a corporation

Application June 5, 1947, Serial No. 752,815

4 Claims. (Cl. 76—105)

1

This invention relates to the manufacture of articles of flatware such as spoons, forks, butter knives and spreaders, cake knives, etc.

In accordance with the usual prior practice in the manufacture of articles of flatware such as those referred to, the articles are first blanked from suitable metal by blanking dies which produce flat blanks. The flat blank is then grade-rolled for providing a flat blank of graded thickness, more particularly, a blank which varies in thickness longitudinally thereof. Said graded blank is then cut to outline by cutting dies corresponding in peripheral edge contour to that of the finished article. Thereafter, the handle part of the blank is shaped in an open die to the form it is to have in the finished article, and said die also impresses the surface ornamentation or design on the handle when the latter is to be provided therewith. After the handle-shaping or striking operation is performed, the other part of the blank, for example, the bowl-forming part thereof in the case of the spoon, is shaped or otherwise operated upon to form such part.

The above described operation of shaping or striking the handle part of the blank in an open die has several disadvantages. Notably among the latter is the formation of a burr or flash along the side edges and outer end of the handle. This burr or flash must, of course, be trimmed off before the silver plating or other finishing operations are performed. Besides the labor and expense of the trimming operation and the subsequent sand-polishing operation required in order to remove the burr or flash and to smooth and polish the handle at its edges, the metal which is removed is largely wasted, and, of course, this waste adds to the cost of production, especially when the articles are made of sterling silver. Moreover, when the handle is provided with surface ornamentation which, as stated, is struck up by the open die simultaneously with the shaping of the handle, such ornamentation or design which is provided on the surface of the handle at the edges thereof is frequently impaired either directly as a result of the formation of the burr or flash or indirectly as a result of the operations performed in trimming off the burr or flash and polishing the side edge and end of the handle. Further, in performing the trimming operation which is usually performed by engaging the edges of the articles with a moving belt-carrying emery or other abrasive trimming medium, the operator usually holds a plurality of the articles in adjacent surface to surface relation while presenting the edges of the handles to the belt for the

2

trimming operation. As a result, the emery carried by the belt penetrates between the adjacent surfaces of adjacent handles of the articles and chafes or scars said surfaces. It will be understood that this chafing or scarring must be removed and that an additional operation is required for this purpose.

One of the objects of the present invention is to obviate the above mentioned and other disadvantages which result from the above described handle-shaping operation. More particularly, in accordance with this object of the invention, the shaping of the handle is performed in such a manner as to obviate the production of a flash or burr on the edge and end of the handle, thus obviating the trimming and polishing operations required to remove the flash or burr. Moreover, pursuant to this object of the invention, the side edges and end of the handle are smoothly planished automatically during the handle-shaping operation. Furthermore, when ornamentation is provided on the handle during the handle-shaping operation, impairment of the ornamentation or design which frequently results by the trimming and polishing operations is obviated.

Another object of the invention is to provide a handle-shaping operation which results in preserving in the finished handle all of the metal contained in the handle-forming part of the blank, so that the handle is thicker than the handle of an article made in accordance with the prior method of shaping the handle in an open die as described above.

A further object is to provide the article with a handle which is thicker along its edges than are handles which are shaped in an open die. More specifically, in this connection, it may be noted that by reason of the thickening of the handle at the edges thereof and by conserving all of the metal of the handle-forming part of the blank in the handle of the finished article, a thinner blank may be used than was heretofore possible without decreasing the stiffness or rigidity of the handle.

A further object of the invention is the provision of a handle-shaping and ornamenting method which results in the provision of the handle with an ornamental design which is more sharply and distinctly brought up and defined than is usually the case with articles which are shaped and ornamented by means of an open die.

A yet further object is generally to provide an improved method of shaping and ornamenting the handles of articles of flatware made from non-ferrous metals and concomitantly to im-

prove the construction and appearance of such articles.

The above and other objects, features and advantages of the invention and objects ancillary thereto will be fully understood from the following description considered in connection with the accompanying illustrative drawings.

In the drawings:

Fig. 1 is a side view of a die embodying the present invention and particularly well adapted for use in performing the method of this invention;

Fig. 2 is a sectional view on the line 2—2 of Fig. 1, showing the operation of the die, in accordance with the present invention, for shaping the handle of the article;

Fig. 3 is a sectional view, on a larger scale, on the line 3—3 of Fig. 2;

Fig. 4 is a sectional view, on a greatly enlarged scale, on the line 4—4 of Fig. 2;

Fig. 5 is a perspective view showing the companion parts of the die and a flat article blank, said parts of the die and said blank being separated from each other for the purpose of illustration;

Fig. 6 is a side edge view of the blank after the handle-forming part thereof is shaped in accordance with the present invention;

Fig. 7 is a front view of the finished article, shown as a spoon;

Fig. 8 is a view of the back of the finished article;

Fig. 9 is an edge view of the finished article.

The present invention is hereinafter particularly described with reference to the manufacture of spoons as the selected illustrative articles but it will be understood that the invention is similarly applicable to other articles of flatware such as forks, butter knives or spreaders, cake knives, etc. The articles are produced from flat blanks made of non-ferrous metal, for example, but without limitation, nickel silver and sterling silver which are metals commonly employed for making flatware. These article blanks are customarily rolled in accordance with known practice to a graded thickness longitudinally of the blanks, but the latter do not vary in thickness along any line running laterally of the blank.

In accordance with the method of the present invention the flat grade-rolled article blank B shown in Fig. 5 is operated upon in a closed die of a power-operated die-press for shaping the handle part of the blank to the desired shape and for simultaneously impressing a surface design if the handle is to be provided therewith. More particularly, the handle part of the blank is pressed between the confronting surfaces of the upper and lower die-punches 10 and 12, respectively, while the handle is confined edgewise thereof by a rigid peripheral wall 14 of the same peripheral contour as that of the peripheral edge of the handle part of the finished article. Said wall 14 defines an opening in the stationary die plate 16. Said opening is of substantially the same size as the article blank and corresponds in shape to the peripheral edge contour thereof but said blank is preferably slightly smaller than said opening to provide clearance for the insertion of said blank in said opening preliminary to the operation of the die-punches 10 and 12 thereon.

As shown in Fig. 2 the confronting or striking surfaces 18 and 20 of the die-punches 10 and 12, respectively, are curved longitudinally for imparting the desired longitudinal curvature to the

handle-forming part of the blank in relation to the other part thereof which in the illustrative article, is the bowl-forming part of the blank. Further, when the handle of the spoon or other article of flatware is to be provided with surface ornamentation or designs said surfaces 18 and 20 of the die-punches are suitably formed as illustrated in Figs. 4 and 5 for impressing the surface designs in the handle-forming part of the article simultaneously with the shaping operation of said die-punches. As here shown, the front and back surfaces of the handle are struck by the die-punches 12 and 10, respectively, but it will be understood that the punches may be reversed in respect to their operation on said surface of the handle-forming part of the blank. Also it will be noted that the die-punch, in this case the upper die-punch 10, which strikes the back of the handle is provided with longitudinally extending narrow recesses 22 (Figs. 4 and 5) in its surface 18 at the opposite side edges of the latter so as to provide the marginal side edges of the handle with narrow ribs 24 which project beyond the back surface 26 of the handle, so that the side edges of the handle are thickened, the outer surfaces of said ribs being continuous with the side edge surfaces 28 of the handle.

The operation of the punches 10 and 12 on the handle-forming part of the blank within the opening defined by the peripherally continuous wall 14 of die plate 16 produces a handle which is shaped as desired, in accordance with the relative longitudinal contours of the confronting surfaces 18 and 20 of the die-punches 10 and 12, respectively, and at the same time the side edges 28 and the end edge 30 of the handle are smoothly planished since that part of the die plate opening in which the punches 10 and 12 operate is completely filled by the corresponding part of the die blank pursuant to the striking and coining operation thereon of the die punches in said peripherally continuous opening of said die plate.

In the illustrated apparatus, the die punch 10 is fixed to and carried by a holder 32 which is secured to the vertically movable member 34 of the die press. Said member 34 is guided for vertical movement by a plurality of vertical guide posts 36, one of which is shown in Fig. 1. The die-punch 12 is integral with or fixed to the base 38 which has a limited vertical guided movement in the recess 40 of a rigid, stationary block 42. The latter is rigidly secured to the bed 44 of the press in any suitable way as by a plurality of shoulder screws 46. A plurality of compression springs 48 and companion guide pins 50 are associated with the base 38 of the die-punch 12 for moving the latter upwardly to move the shaped article to the top of the opening in die plate 16 after the operation of the die-punches on said article, so that the shaped article may be conveniently removed. In this connection it will be noted that the downward movement of the die-punch 12 is limited by the engagement of the lower end 52 of the base of said punch with the surface 54 of the stationary block 42, and that the upward movement of said die-punch 12 is limited by the engagement of the shoulder 56 of the base 38 of said die-punch with the lower surface 58 of die plate 16. It will be understood that in the operation of the apparatus, the first part of the down stroke of punch 10 clamps the blank against the punch 12 and then as punch 10 continues to move it moves punch 12 against the pressure of springs 48 to the rigid abutment provided by surface 54 of block

The part of the punch 10 which is movable in the opening of die plate 16 has a close sliding fit at the opposite sides 60 and at its end 62 with the adjacent portions, respectively, of vertical wall 14 of the die plate 16. Similarly the lower die-punch 12 has a close sliding fit in the opening in die plate 16, the opposite sides 64 and the end 66 of said die-punch being in sliding engagement with the adjacent portions, respectively, of vertical wall 14 of the die-plate. It will be understood, of course, that the vertical surfaces of the die-punches which are in sliding engagement with the adjacent surface portions, respectively, of vertical wall 14 are parallel to said wall portions, respectively. By reason of this interfitting sliding engagement of the die-punches with the wall 14 of die plate 16, the part of the blank which is struck by said punches is confined entirely to the space between said punches laterally of the striking surfaces of said punches, so that no flash or burr is formed at the side edges of the handle. The upper edge of wall 14 may be and preferably is slightly tapered or flared upwardly, as indicated at 68 in Figs. 2, 4 and 5, for the purpose of facilitating the removal of the struck blank from die plate 16.

After the article blank is operated upon by the die punches as hereinbefore described for shaping the handle of the article and for ornamenting the surface of said handle, when such surface ornamentation is desired, the blank with the shaped handles is then subjected to the usual operations for forming the other part of the article. For example, in the case of the article herein selected for illustrative purposes as the spoon, the part 70 of the blank is operated upon in the usual way to form the bowl 70a of the spoon (Figs. 7 and 8). If the article is to be silver plated it may then be subjected to the usual silver plating process without the intermediate trimming and sanding operations heretofore required in the manufacture of articles involving the use of an open die for shaping the handle. It will be noted that the design or ornamentation which is provided immediately at the edges of the handle, as indicated, for example, at 72 in Fig. 7 is preserved intact without impairment, since, in accordance with the present invention the shaping of the handle is accomplished without the production of a burr or flash. Moreover, it will be noted that all of the metal of the blank is preserved in the handle so that the latter instead of being thinner than the handle-forming part of the blank is thicker than the handle of a similar article which is operated upon in an open die in accordance with prior practice. Further it will be observed that the handle is somewhat thicker at its side edges than a handle shaped in an open die from a blank of the same grade-rolled thickness, and that for this reason the articles produced in accordance with the present invention are not only actually thicker than handles of articles shaped in an open die but have the appearance of being thicker and heavier than they actually are. In this connection it will be understood that this is of special advantage and value especially when the articles are made of sterling silver. In any event, however, and irrespective of whether the articles are made of sterling silver or of nickel silver or other appropriate non-ferrous metal, the preservation of all of the metal of the blank in the finished article, as well as the thickening of the edges of the handle are highly advantageous and valuable since it is possible to use a thinner blank than was heretofore possible without decreasing the stiff-

ness of the handle in comparison with the stiffness of handles formed in an open die in accordance with prior practice. It is also important to note that, in accordance with the present invention, as hereinbefore described, the side edges of the handle are smoothly planished so that, as stated above, it is unnecessary to trim the handle at its side edges or even to polish the latter before the final overall polishing of the article. It will be understood, however, that it is within the scope of the present invention to provide the vertical wall 14 of the die plate 16 with a series of parallel shallow vertical grooves in case it is desired to correspondingly shape the side edges of the handle.

It will be understood that various changes may be made in the die apparatus and in the mode of practicing the method of the present invention without departing from the underlying idea or principles thereof within the scope of the appended claims.

Having thus described my invention, what I claim and desire to secure by Letters Patent is:

1. In the manufacture of articles of flatware such as spoons, forks, butter knives, and spreaders, cake knives, etc., from non-ferrous metal blanks, the method which comprises placing a peripherally shaped blank of variable thickness in a die opening closed at its peripheral side, with the edges of the handle-forming part of the blank lying close to and confined by the adjacent portions, respectively, of the side-closing wall of said opening, and striking said handle-forming part at the opposite sides thereof in said opening between die-punches operable on said part in said opening to shape said part to the desired form and to increase the thickness of the marginal side edges of the handle-forming part of the blank.

2. In the manufacture of articles of flatware such as spoons, forks, butter knives and spreaders, cake knives, etc., from non-ferrous metal blanks, the method which comprises placing a peripherally shaped grade-rolled blank in a die-opening closed at its peripheral side, with the edges of the handle-forming part of the blank lying close to and confined by the adjacent portions, respectively, of the side-closing wall of said opening, and striking said handle-forming part at the opposite sides thereof in said opening between handle-shaping die-punches which slidably engage said wall portions in interfitting relation therewith whereby the metal of said handle-forming part is confined entirely between said die-punches and said wall portions of the die and the edges of the handle are planished by said wall portions, one of said punches having longitudinally extending recesses at the side edges of its striking surface whereby the marginal side edges of the handle-forming part of the blank are thickened by said striking operation of said punches on said part of the blank.

3. In the manufacture of articles of flatware such as spoons, forks, butter knives and spreaders, cake knives, etc., from non-ferrous metal blanks, the method which comprises placing a peripherally shaped grade-rolled blank in a die-opening closed at its peripheral side, with the edges of the handle-forming part of the blank lying close to and confined by the adjacent portions, respectively, of the side-closing wall of said opening, and striking said handle-forming part at the opposite sides thereof in said opening between die-punches operable on said part in said opening to shape said part to the desired form

and to simultaneously impress a surface design thereon and to increase the thickness of the side edges of the handle-forming part of the blank.

4. In the manufacture of articles of flatware such as spoons, forks, butter knives and spreaders, cake knives, etc., from non-ferrous metal blanks, the method which comprises providing a blank of the finished peripheral contour and of variable thickness, and thereafter pressing and edging the handle part of the blank to the desired shape between the confronting surfaces of die-punches disposed at opposite sides, respectively, of said handle part with the handle close to and confined edgewise thereof by a rigid peripheral wall of the same peripheral contour as that of the peripheral edge of the handle part of the article, one of said punches having longitudinally extending recesses at the side edges of its striking surface whereby the side edges of the handle-forming part of the blank are thickened by said striking operation of said punches on said part of the blank.
